SEAL FOR FABRIC PROCESSING MACHINES

Henry H. Iler, Greenville, S. C., assignor, by mesne assignments, to Reconstruction Finance Corporation, Boston, Mass., a corporation of the United States

Application April 30, 1938, Serial No. 205,219

3 Claims. (Cl. 68—5)

This invention relates to a fabric processing machine such for instance as an ager; and has for one of its objects the sealing of the entrance opening through which the fabric passes to prevent the influx into the working chamber of outside air or gases and to prevent fumes or vapors in the working chamber from mixing with air about the machine.

Another object of the invention is to provide a machine of this character which may be operated in a room or building with other machinery of a different character, rather than isolating the machine because of the fumes which may come from the machine and contaminate the surrounding air.

Another object of the invention is to provide a seal against the interchange of gases inside and outside the machine, which seal will be out of contact with the work and thus will remove a cause of smearing the work in cases where the work has been freshly printed or dyed.

Another object of the invention is to prevent any condensation which may occur on the walls of the machine from running down and dripping on the work that the condensate may spot the work.

Another and more specific object of the invention is to collect the gases in and about the work at the entrance opening to the machine and carry them to some remote point where they may be discharged that neither the surrounding outside air may enter the machine or the vapors or gases in the machine may exude therefrom into the outside air.

Another and more specific object of the invention is to control the amount of pick-up of these gas collectors by adjusting the same so that the desired pick-up of gases in and about the entrance opening may be had.

Another object of the invention is to raise the temperature of the ingoing fabric in order that a higher temperature inside of the machine will not cause vapors to condense on the otherwise cooler ingoing fabric surfaces before the fabric contacts with the first carrier roll inside of the machine, thereby often avoiding the smearing of freshly printed or dyed fabrics which are being treated.

With these and other objects in view, the invention consists of certain novel features of construction, as will be more fully described, and particularly pointed out in the appended claims.

In the accompanying drawings:

Fig. 1 is an end elevation of a machine equipped with the sealing apparatus of this invention;

Fig. 2 is a side elevation of a fragmental portion of the machine with other parts broken away showing the relation of the operating parts;

Fig. 3 is a sectional view of a fragmental portion of the machine through the entrance wall and sealing means showing the relation of the operating parts on a larger scale;

Fig. 4 is an elevation of one of the heaters;

Fig. 5 is a front elevation of one of the collecting tubes.

In the processing of textile fabrics it is usual to pass the web of fabric through what is known as an ager, or other processes may be had upon the fabric in finishing the same wherein the fabric enters some closed chamber and is exposed to steam, or vapors of a chemical nature. In order that the web of fabric may enter the chamber and pass therefrom, some opening must be provided, and this opening often permits some passage of the gases within the chamber to the outside, and some of the air outside into the chamber, which exchange is accentuated by the movement of the web of work through the opening; and in order to reduce this exchange of gases to a minimum, it is desirable to seal such opening, and sometimes rolls are used adjacent to the opening with which the work contacts. Rolls have a disadvantage in that smearing of freshly printed or dyed fabrics may occur before the dye has become sufficiently set to prevent such smearing; and accordingly, in order to provide both a better seal, and a seal which will not contact the work, I have arranged tubular collectors which will pick up gases adjacent the opening, and thus any air tending to enter the chamber will be picked up by my collectors, and any gases which escape from the chamber will be picked up by my collectors, and by picking up all of the gases in this manner adjacent the opening I find that no exchange of gases takes place; and I may adjust these collectors in such a manner as to control to a large extent the amount collected, so that the desired effective results may be had; and the following is a more detailed description of the present embodiment of this invention, illustrating the preferred means by which these advantageous results may be accomplished:

With reference to the drawings, 10 designates generally the ager to which this invention is applied, which comprises a chamber having enclosing walls that the treatment of the fabric as it passes in a zigzag manner over rolls within the chamber may be had. The chamber has side, bottom, top and end walls. The end wall

with which we are concerned is designated 11 and provided with a slot 12 extending horizontally in this end wall 11, and of a length to adequately receive the fabric in its full woven width. This opening is illustrated on a somewhat larger scale in Fig. 3 and is of a dimension across it sufficient to permit the exit web of fabric 13, and the entering web of fabric 14, to both pass through the opening 12 at the same time, and both out of contact with the edge walls of the opening or the other apparatus which is to be hereinafter described.

It sometimes happens that condensed vapors from along the inner surface 15 of the wall 11 run down the inner wall and drop upon the exiting web of fabric 13; and in order to catch any such condensate I provide a lip or trough 16 (see Fig. 3) which extends inwardly and upwardly from the wall 11 to a substantial extent and also completely through the wall and again upwardly to provide a trough 17. To more fully seal the collector trough or lip 16 against the entrance of any air, plastic material 56 is positioned between the wall of the chamber and the outwardly extending portion 57 of this generally S-shaped part, that a more effective seal may be provided. In order to disperse any collection of such liquid which may trickle down the inside wall 11 and collect in trough 17 I provide a heating chamber 18 located in the wall within the trough 17 and adjacent the opening 12, which chamber receives steam through entrance pipe 19 to heat the same, any condensation or unused steam passing out through pipe 20. There is also a heating chamber 21 located within the wall 11 below the opening 12 similarly supplied with steam for maintaining the wall warm and in a condition to evaporate any condensate which may form about this opening.

In order to collect gases which may escape through the opening 12 or collect outside gases or moisture from the fabric tending to enter the chamber as the fabric passes into the chamber I have provided tubular collector members 25 and 26 extending from and rotatably mounted in a common conduit tube 27 into which the collector members 25 and 26 discharge. Each of these tubes is closed at its end distant from conduit 27 and is slotted as at 28 and the tubes are located close to the wall 11, the tube 25 being just above and the tube 26 being just below the horizontal plane of the upper and lower edges of opening 12, they being spaced sufficiently so as to be out of contact with the webs of fabric as it passes into or from the working chamber. By rotating these tubes to the desired position by any means, such as handles 32, the slots 28 may be brought closer to or further from the fabric but will always be within a relatively short arc from the position shown in Fig. 3 for best accomplishing their desired result. This rotation is accomplished manually by grasping the handles 32 and moving them until the slot is in the desired location to pick up the gases in its vicinity.

Steam pipes for heating the gases as they enter the collector members 25 and 26 are designated 35 and 36 and pass lengthwise through the collectors 25 and 26 and are located on either side of and closely adjacent the slot 28 so as to heat the lips of the slot and prevent possible condensation of vapor on the lips, rather causing any re-evaporation of any condensate on the inside of the collector members. These steam pipes 35 and 36 are joined by a U-piece 37 at one end and

are flexibly connected at the other end to a steam supply source, as will be further described.

An additional function of collector tube 26 and of heating chamber 21 is that of raising the temperature of ingoing fabric in order that the inside temperature of the machine to which the seal is applied will be adversely affected as little as possible and to prevent possibility of vapors being condensed upon the relatively cooler ingoing fabric surfaces after entrance and before contacting the first carrier roll inside of the machine. This feature assists materially in the avoidance of color smearing of freshly printed or dye fabrics being treated.

The common exhaust conduit for both of these collector members is operated by an exhaust fan 38 at its upper end which is driven by motor 39 to draw upwardly gases which may be collected by the collector members 25 and 26 and reduce the pressure in these collectors sufficiently so that they will pick up whatever gases are present in the areas 40. The so collected gases are exhausted at some remote point into the atmosphere through a conduit 41 that they will not disturb or contaminate the air about the machine, making it unnecessary for isolation of the machine in some location.

The exhaust conduit 27 is provided with a drain 42 for condensed vapors which is of S-shape as at 43, to provide a liquid trap and seal the exhaust conduit 27 while permitting discharge of any collected moisture through the discharge pipe 44.

Conduit 45 is connected with a steam source 35 for the supply of steam to the fixed heaters 18 by their connections 19 which are controlled by gate valve 46. Steam is supplied to the steam pipes 36 and 35 serially through the conduit 47 controlled by valve 47'. There is a flexible connection as at 48 to the first pipe 36. The pipe 35 from the upper collector 25 is connected to the upper pipe 36 of the lower collector 26 by a flexible connection 49, and there is a flexible connection 50 from the heating pipe 35 of the second collector 26 leading from this collector. These connections are of sufficient flexibility to permit rotary adjustment of the collectors to position the slotted tube as desired. The discharge conduit from the collector tubes 51 and the discharge conduit 52 from the heating tubes 18 are connected together as at 53 to a steam trap 54 and then back through pipe 55 to the plant's condensate return system or discharged to the atmosphere.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. In a fabric processing machine having a working chamber formed by enclosing walls, one of said walls having an opening therein through which the web of fabric passes, spaced hollow collector members disposed on opposite sides of the traveling work each provided with a slot, suction means to cause the gases adjacent the work to be picked up by said members and conducted to some remote location, and heating means disposed along the edge of the slot of each of said collector members.

2. In a fabric processing machine having a working chamber formed by enclosing walls, one

of said walls having an opening therein through which the web of fabric passes, a hollow collector member provided with a slot disposed adjacent to but out of contact with the work and in close proximity to said opening, means to cause the gases adjacent the work and said opening to be picked up by said member, and means to rotatably mount said member to position said slot in different positions relative to said work.

3. In a fabric processing machine, a working chamber formed by enclosing walls, one of said walls having an opening therein through which

the web of fabric passes, a collector member outwardly of and adjacent said opening and a trough adjacent said opening consisting of sheet material extending through the wall and inwardly thereof for collecting drip on the inner surface of said wall and extending outwardly of the wall and engaging the collector member in a sealing manner, means providing a seal between the trough and the wall exterior of the wall, and heating means in said trough for evaporating the drip collected.

HENRY H. ILER.
